UNITED STATES PATENT OFFICE.

WILLIAM M. HOFFMAN, OF BUFFALO, NEW YORK, ASSIGNOR TO GENERAL FUEL APPARATUS CORPORATION, OF BUFFALO, NEW YORK, A CORPORATION OF DELAWARE.

HYDROCARBON-BURNER.

1,401,404.

Specification of Letters Patent. Patented Dec. 27, 1921.

Application filed June 7, 1920. Serial No. 387,003.

To all whom it may concern:

Be it known that I, WILLIAM M. HOFFMAN, citizen of the United States, residing at Buffalo, county of Erie, State of New York, have invented a certain new and useful Improvement in Hydrocarbon-Burners, and declare the following to be a full, clear, and exact description of the same, such as will enable others skilled in the art to which it pertains to make and use the same, reference being had to the accompanying drawings, which form a part of this specification.

My invention relates to improvements in hydrocarbon burners. The object is to provide a burner capable of advantageously utilizing the cheaper, lower grade fuel oils.

A further object is to provide a simple, inexpensive fuel oil burner adapted to utilize the heavier grades of fuel oil with a maximum heat efficiency and leaving a minimum of residue.

A further object is to provide a fuel oil burner for the heavier, lower grade oils of such a character that it will operate efficiently without requiring the services of an attendant.

A further object is to provide a fuel oil burner in which the fuel oil is burned in the interior of a hollow combustion chamber, through the porous refractory wall of which said fuel has been permitted to percolate to such interior.

A further object is the provision of a fuel oil burner, in which the fuel oil is permitted to percolate through the wall of a hollow combustion chamber of such a character that the temperature of the fuel is materially increased, being brought substantially to the point of volatilization before it reaches the interior of the chamber.

These and other objects of the invention, together with details of construction, will more fully appear from the following description, appended claims and accompanying drawings, in which:

Figure 1 is a vertical section through my burner.

Fig. 2 is a section taken on the line 2—2 Fig. 1.

Fig. 3 is an elevation of the burner from the rear.

Fig. 4 is a section taken on the line 2—2, Fig. 1, showing a modification.

In the accomplishment of the above objects

I employ a hollow combustion chamber in the interior of which the fuel is burned, which combustion chamber is composed of a porous refractory substance. The fuel oil is brought to the outer surface of the combustion chamber wall and permitted to percolate therethrough. The porous refractory substance which composes the wall is of such a texture and porosity that the liquid fuel as it percolates therethrough is brought substantially to the point of volatilization. As fuel enters the interior of the combustion chamber it is mixed with the steam which enters from a steam jet positioned at one end of the chamber and it is burned therein producing an intense heat with approximately perfect combustion. The burning products of combustion issue from the open end of the combustion chamber opposite the end at which the steam jet is positioned and the combustion chamber is left practically free of any residual matter.

In the embodiment of the invention here shown the combustion chamber is in the form of a hollow cylinder. It is apparent however that it might be of any other shape in cross sectional area as well as circular.

As a convenient means of feeding the fuel to the outer surface of the burner wall I prefer to provide a jacket for the combustion chamber to which the fuel oil is fed, and from which it percolates to the outer surface of the wall of the combustion chamber. This jacket also serves as a container within which the fuel is heated before it enters the wall of the combustion chamber thereby facilitating its flow and assisting in bringing the fuel to the combustion point.

Let *a* indicate a casing, here shown in the form of a hollow cylinder, adapted to receive a removable hollow core *b* composed of suitable porous refractory material. This casing is jacketed, and is here shown as being jacketed but for a portion of its length as shown at *c*. This jacket is supplied with fuel oil through a conduit *d* from some convenient source of fuel oil supply. The casing wall adjacent the jacketed portion is perforated as at *e* to permit the passage of fuel therethrough to the surface of the porous refractory core, interior thereof.

Disposed axially at the rear of the burner casing is a nozzle *g* supplied through conduit *h*, either with air from conduit *h*

- which leads to a convenient source of air supply through which inflow of air will be regulated by means of a valve h^3 ; or through an additional conduit i with steam under pressure from a suitable source of supply, the passage of steam therethrough being regulated by means of a valve i^2 . A shutter valve h leading to the atmosphere encircles this nozzle at the rear of the casing, apertures in which are adapted to register upon manipulation, with apertures in the casing to admit air therethrough to the interior of the burner. This nozzle is adapted to project a jet of steam or air under pressure through the burner along the face of the burner wall so as to thoroughly mix such air or steam with the burning particles of hydrocarbon in the combustion chamber.
- 20 In the operation of this device fuel is supplied to the jacketed wall of the casing, from where it passes through apertures e , to the porous refractory core through which it percolates to the interior surface thereof where it is burned. In Fig. 2 this jacketed portion is shown with a median wall f adapted to prevent the oil from flowing downwardly into the lower portion of the jacket, where it would collect and cause
- 25 a surplus or overflow of oil in the lower portion of the burner. This retaining wall causes the liquid fuel to enter the porous core along the upper portion thereof, forcing the same to percolate downwardly therethrough into the lower half of the core.

In the modification shown in Fig. 4 the restraining influence of this wall is relieved by the provision of apertures therethrough so that a small portion of the oil may flow 40 through to the lower section of the jacket, where it would pass through perforations in the casing to the porous core. The lower portion of the jacket, shut off by the wall f as shown in Fig. 2, performs no necessary 45 useful function as will be apparent and might well be omitted.

By experimentation, I have found that the use, in this type of burner, of a hollow core of porous refractory material, prevents to a large degree the formation of carbon on the face thereof, such as results when oil is burned in the perforated metal casing after having passed through a porous refractory filler contained in said casing. In the use 55 of my form of core the fuel oil escapes along the inner surface of the core through an infinite number of pores after having been heated to a point substantially close to the point of volatilization, and the particles 60 of hydrocarbon do not have an opportunity to collect and carbonize as occurs with the use of a perforated metal plate. The core is formed of such size, and bound together in a texture, such as has been found to be 65 suitable for the character of fuel to be used.

A coarse open texture of core material permitting free passage of oil therethrough and being of limited extent would be suitable for certain grades of fuel easily volatilized, where the reverse would be true were the fuel more difficult to reduce to a gas. The core itself is removable in order that it may be cleaned, cores being of standard size.

What I claim is:

1. In a hydrocarbon burner, a combustion chamber in the form of a hollow refractory, porous core, a vapor jet producing means positioned at one end thereof adapted to project a jet of vapor therein, an encircling casing for such core provided with a jacketed portion, the inner wall of such jacket perforated to permit the passage of fuel therethrough to the core, means for supplying fuel to said jacketed casing.

2. In a fuel oil burner, a combustion chamber in the form of a hollow refractory, porous core, a jacketed casing therefor adapted to contain liquid fuel, means for supplying liquid fuel thereto, apertures through said casing to permit the passage of fuel from the jacket to the outer surface of the core, means for projecting a jet of vapor through the core along the face thereof.

3. In a fuel oil burner, a hollow cylindrical combustion chamber open at one end, the wall of said chamber formed of a porous refractory material adapted for the percolation of fuel oil therethrough.

4. In a fuel oil burner, a hollow cylindrical combustion chamber open at one end, 100 said combustion chamber formed of a porous refractory material adapted for the percolation of fuel oil therethrough, a casing for such combustion chamber the upper portion of which is partially jacketed to serve as a 105 container for fuel oil, fuel oil communicating passages through the wall of said casing to the outer surface of the combustion chamber, jet producing means positioned at the end of the combustion chamber opposite 110 the open end.

5. In a hydrocarbon burner, a combustion chamber, the wall of which is of refractory material adapted for the percolation of fluid therethrough, a casing for such combustion chamber adapted to contain fuel oil and provided with means for receiving fuel, and perforated to permit the passage of oil therethrough to the outer surface of the wall of the combustion chamber, means for projecting a steam jet into one end of said combustion chamber.

6. In a fuel oil burner, a hollow refractory porous combustion chamber, a fuel oil container positioned so as to be heated thereby 125 and adapted for the passage of fuel therefrom to the outer surface of the wall of said chamber so same may percolate therethrough, means for forcing a vapor jet through such chamber.

7. In a fuel oil burner, a hollow combustion chamber the continuous encircling wall of which is composed of a porous refractory material through which liquid fuel may be fed to be burned on the interior thereof.
8. In a fuel oil burner, a hollow combustion chamber composed of a porous refractory material of such a character that fuel oil may percolate therethrough to be burned in the interior of said chamber, said combustion chamber open at one end, means for projecting a vapor jet into the other end of said chamber.
9. In a fuel oil burner, a hollow combustion chamber the continuous encircling wall of which is composed of a porous refractory material of such character that fuel oil may percolate therethrough to be burned in the interior thereof, means for supplying liquid fuel to the outer surface of the wall of said combustion chamber.
10. In a hydrocarbon burner, a combustion chamber in the form of a hollow refractory, porous core, means for bringing fuel oil to the outer surface of the wall thereof so it may percolate therethrough, means for projecting a vapor jet into one end of said core.
11. In a fuel oil burner, a hollow combustion chamber in the interior of which combustion takes place, the wall of said chamber composed of a porous, refractory material adapted for the percolation of liquid fuel therethrough, said combustion chamber open at one end, a vapor jet producing means positioned at the opposite end of said chamber, said end of the combustion chamber provided with air draft openings.
12. In a fuel oil burner, a hollow combustion chamber in the interior of which combustion takes place, said combustion chamber comprising a wall composed of a porous refractory material adapted for the percolation of liquid fuel therethrough and being open at one end, and a vapor jet producing means positioned at the other end of said
- chamber, air draft regulating means also positioned at said end of the chamber.
13. In a fuel oil burner, in combination, a hollow casing, the upper portion of which is jacketed to provide a container for fuel oil, means for supplying oil thereto, a hollow combustion core composed of porous refractory material carried interiorly said casing, the inner wall of the jacket portion of said casing perforated so that fuel oil may pass therethrough, means for projecting a vapor jet into one end of said casing, the other end of said casing being open.
14. In a fuel oil burner, in combination, a hollow casing partially jacketed to provide a container for fuel oil, communicating passageways through the inner wall of the jacket portion of said casing, a combustion chamber in the form of a porous refractory core open at one end adapted to be removable received within said casing, vapor jet producing means positioned so as to project a jet of vapor into the interior of said casing.
15. In a hydrocarbon burner, a partially jacketed casing, the upper portion of which jacket is provided with means from which the same may be supplied with liquid fuel, a baffle wall in such jacketed portion to restrain the free passage of fuel to the lower section of such jacket, the inner wall of such jacket portion perforated to permit the passage of fuel therethrough, a combustion chamber comprising a hollow porous refractory core removably carried within said casing, a vapor jet-producing means positioned at one end of said combustion chamber to project a vapor jet therethrough, an air draft shutter positioned at such end to regulate the admission of air to such combustion chamber, means for supplying fuel oil to such jacketed portion of the casing.

In testimony whereof, I sign this specification.

WILLIAM M. HOFFMAN.
